UNITED STATES PATENT AND TRADEMARK OFFICE
Certificate

Patent No. D. 682,410 S

Patented: May 14, 2013

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: James Hester, Marmaduke, AR (US) and Randy R. Guthrie, Pocahontas, AR (US).

Signed and Sealed this Seventeenth Day of June 2014.
